UNITED STATES PATENT OFFICE.

VINCENT P. TRAVERS, OF NEW YORK, N. Y.

HAMMOCK.

SPECIFICATION forming part of Letters Patent No. 244,690, dated July 19, 1881.

Application filed June 22, 1881. (No model.)

To all whom it may concern:

Be it known that I, VINCENT P. TRAVERS, of New York, in the county and State of New York, have invented an Improved Hammock, 5 of which the following is a specification.

Figure 1 is a perspective view of my improved hammock. Fig. 2 is a top view of portion thereof; and Fig. 3, a cross-section of the same on the line *c c*, Fig. 2.

10 This invention relates to a new construction of a hammock, and has for its object to avoid the costly interweaving of the cords that make up the body of the hammock, and to substitute therefor a system of longitudinal cords and cross-bands, so arranged that the cross-bands have tubular openings to allow the longitudinal cords to be passed through them, in this manner obtaining the proper spacing of the longitudinal cords and great durability of the 15 entire fabric. The longitudinal cords of the hammock are at the ends made to converge, and are there continued into the fastening-rope, if desired, or secured to a suitable ring, and by their converging they are brought into 20 oblique positions, whereby they will prevent the cross-bands from slipping out of the position assigned to them respectively.

25 In the accompanying drawings, the letters *A A* represent the longitudinal cords of the hammock, and the letters *B B* the cross-bands of the same. Each longitudinal cord is a cord of usual construction. The cross-bands are made with tubular openings through them, so that the cords *A* can be passed through them, as indicated in Figs. 2 and 3. The tubular 30 passages through the cross-bands are preferably at equal distances apart, as shown, and the cords are passed through them with the aid of a suitable needle, or otherwise. There is nothing new in weaving the cross-bands *B* with the tubular passages, as such fabrics are 35 of common construction. The cords *A* converge at the ends of the hammock and are united at the knots *a*. Beyond these knots 40 the cords may be braided or twisted into ropes *C*, by means of which the hammock can be

suspended from suitable supports; but instead of making the ropes *C* from the continuations of the cords *A* the cords may, where they join, be united to a ring, to which suitable fastening-ropes may be secured. The cords *A* converging prevent the cross-bands slipping on them, and the cross-bands always hold the cords at the desired distances apart.

45 In the body of the hammock it is not essential that the cords *A* should be parallel to each other, as in Fig. 2, as the central bands, *B*, may be made longer than the bands that are nearer to the ends of the hammock; but good results will also be produced by making the 50 bands *B* all of equal length.

55 A hammock constructed on this system will be much more durable than the ordinary Mexican hammocks that are so much used, and far less liable to get out of order. If one of the 60 cords *A* breaks the hammock can readily be repaired, whereas with the Mexican or interwoven hammock, if one of the cords breaks the entire structure goes to pieces and cannot well be repaired; and even if one of the bands *B* in the improved hammock should be broken, torn, or worn through, it will be easily replaced by another by simply untying the cords at the knot and slipping a new band into position.

75 I claim—

1. A hammock constructed of longitudinal cords *A*, that converge at the ends, and of cross-bands *B*, having tubular passages through which the cords *A* are drawn, all arranged substantially as herein shown and described. 80

2. A hammock composed of longitudinal cords *A* and cross-bands *B*, the longitudinal cords converging at the knots *a*, and of the ropes *C C*, which are formed by twisting the ends of the cords *A* beyond the said knots, 85 substantially as specified.

This specification of my invention signed by me this 21st day of June, 1881.

VINCENT P. TRAVERS.
